FIG. 1 is a front, top, left isometric view of the new design.

FIG. 2 is a rear, top, left isometric view of the new design.
FIG. 3 is a left side view of the new design.
FIG. 4 is a right side view of the new design.
FIG. 5 is a front view of the new design.
FIG. 6 is a rear view of the new design.
FIG. 7 is a top view of the new design.
FIG. 8 is a bottom view of the new design.

FIG. 9 is a front, top, left isometric view of the new design, shown together with an associated liquid container; and,
FIG. 10 is a left side view of the new design, shown together with an associated liquid container, and with the right side view being the mirror image thereof.

The dashed lines shown in the drawings illustrate portions of the beverage container cap (e.g., the drink spout closure and trigger) that form no part of the presently claimed design (FIGS. 1-10) and illustrate environmental structure of an associated liquid container (FIGS. 9-10) that forms no part of the presently claimed design.
